UNITED STATES PATENT OFFICE.

DAVID FRAME LAUGHLIN, OF CLYDE, KANSAS, ASSIGNOR OF ONE-HALF
TO FRANKLIN H. BUTLER, OF CLYDE, KANSAS.

TELEPHONE SIGNAL APPARATUS.

No. 799,658.

Specification of Letters Patent.

Patented Sept. 19, 1905.

Application filed June 13, 1905. Serial No. 265,062.

To all whom it may concern:

Be it known that I, DAVID FRAME LAUGHLIN, a citizen of the United States, residing at Clyde, in the county of Cloud and State of Kansas, have invented a new and useful Telephone Signal Apparatus, of which the following is a specification.

This invention relates to selective signaling systems, and has for its principal object to provide what may be termed a "sympathetic" system, wherein the vibrations of duplicate pendulums subject to the same influence are employed for the purpose of closing electrical circuits.

It is well known that simple pendulums of precisely the same construction and subjected to the same influences will have the same amplitude of vibration and will move through equal arcs in the same time. This fact is taken advantage of in the present instance by employing at a number of stations pendulums of different character—that is to say, the responsive pendulum at each station differs either in length, weight, or size from all of the other pendulums in the remaining stations, and at a central station are arranged a number of calling-pendulums that are duplicates of those in the remaining stations. The term "calling-pendulum" is employed throughout the specification and claims to designate a pendulum which is set in motion at the central station for the purpose of calling another station, and the term "responsive" pendulum is employed to designate a pendulum which vibrates sympathetically with the calling-pendulum, and is moved at a distant station to control the circuit at that station.

The principal object of the invention, therefore, is to provide a simple form of selective signaling system, whereby any selected station may be placed in communication with another without the knowledge of any of the intervening stations, this being of especial value on party-lines where in ordinary systems a call made by one subscriber is sounded at all of the other stations along the line.

With these and other objects in view, as will more fully hereinafter appear, the invention consists in certain novel features of construction and arrangement of parts herein-after fully described, illustrated in the accompanying drawings, and particularly pointed out in the appended claims, it being under-

stood that various changes in the form, proportions, size, and minor details of the structure may be made without departing from the spirit or sacrificing any of the advantages of the invention. 55

In the accompanying drawings, Figure 1 is a diagram of a selective signaling system arranged in accordance with the invention. Fig. 2 is a detail perspective view of the selecting devices employed at each substation. Fig. 3 is a sectional elevation of the same. Fig. 4 is a detail view of a calling mechanism employed at a central station. 60 65

Similar characters of reference are employed to indicate corresponding parts throughout the several figures of the drawings.

All of the local stations are shown as bridged between two main wires 1 and 2, and at station A in Fig. 1 the parts are in the normal position with the receiver-hook down and the talking-circuit disconnected. At station B the selective circuit is shown as connected 75 and the talking-circuit bridged between the main-line wires.

The receiver-hook 3 is pivoted at 4, and it carries at a point intermediate of its length a contact-plate 5, that is insulated from the remaining portion of the hook. Bearing against this contact-plate are two contacts 6 and 7, the contact 6 being connected by a local wire 8 to the main-line wire 2 and the contact 7 being connected by a local wire 9 to the main line 1, and in said local line 9 is connected an electromagnet 10, there being one of such magnets at each of the stations, and the circuit, as indicated at 1, being normally closed through said electromagnet. Within the field 90 of force of the electromagnet 10 is a pendulum 11, which may carry an armature 12. The construction of this portion of the mechanism will be more fully described herein-after. 95

The rear end of the receiver-hook is bent downward, forming an arm 13, that is provided with a shoulder 14, having a small block of insulating material in its upper face, and this block is arranged to receive the front end 100 of a circuit-closing arm 15. The arm 15 is pivoted for swinging movement in a vertical plane and always tends to reassume the same plane, so that when moved outward from the shoulder during a selecting operation it will 105 move inward in order to be in position to be

reengaged by said shoulder, as more fully described hereinafter. This arm when released from the influence of the receiver-hook or when allowed to move downward with the receiver-hook when the receiver is removed will engage a contact-arm 16, and this will close the calling and talking circuits of the line.

At a convenient point in the local station is arranged a call-bell 17, one binding-post of which is connected by a wire 18 to the main-line wire 1. From the other binding-post extends a wire 19 to a contact 20, that is engaged by the receiver-hook when the outer end of the latter is depressed. The circuit is continued when the receiver is on the hook through the hook and through a contact 21 and wire 22 to the circuit-closing arm 15, and if the latter is in engagement with the contact-arm 16 the circuit will be completed through the latter and through wire 23 to the main-line wire 2, so that if the arms 15 and 16 be engaged while the receiver is still on the hook the calling-circuit will be established.

One binding-post of the receiver R is connected by a wire 24 to the contact-arm 15 and the opposite binding-post is connected by a wire 25 to the secondary of the inductorium I and thence to the main-line wire 1. If the contact-arm 15 is down in engagement with the contact-arm 16, the receiver-circuit will be established from main-line wire 1, wire 25, the secondary, the receiver, wire 24, contact-arms 15 and 16, wire 23 to main-line wire 2.

The primary circuit includes a transmitter T, a wire 26, battery B, and contacts 27, that are normally disengaged from the receiver-hook; but when the latter is elevated the primary circuit will be established.

It is a well-known fact that pendulums of different length and of different width and size require different periods of time in vibrating through a complete period. In carrying the present invention into effect, therefore, each responsive pendulum 11 at each of the stations differs in some respect from all of the other responsive pendulums at all of the other stations in the line. It may be longer or shorter or it may have a different period or amplitude of vibration or it may be of different width, and thus be more or less retarded by the air.

Each of the pendulums may be formed of soft iron or may carry a soft-iron armature arranged within the field of force of the electromagnet 10, and when the latter is energized the pendulum will be attracted and when deenergized the pendulum will start its movement toward the position of equilibrium and pass beyond the same by virtue of its acquired velocity. When the first half of a complete period has been reached, the electromagnet is again energized and the pendulum is once more attracted, the magnet being kept ener-

gized during the whole of the second half period of movement and then deenergized exactly at the completion of such half period. It may require two or three or even more movements to effect the desired amplitude of vibration of the pendulum; but in each case the energizing and deenergizing of the electromagnet must occur exactly at the completion of half periods of movement of said pendulum. When the pendulum has finally acquired its predetermined amplitude of vibration, it will strike against the contact-arm 15 and move the same from the shoulder 14 of the receiver-hook, the contact-arm moving by gravity into engagement with the contact-arm 16, and thus, as before described, completing the calling-circuit, so that a current sent along the line will cause the sounding of the bell 17.

To effect movement of the pendulum, the central station is provided with a set of calling-pendulums 11', there being a calling-pendulum the exact duplicate of each responsive pendulum. These calling-pendulums may be arranged in any suitable manner, and when any particular substation is to be called its duplicate calling-pendulum at central is arranged within the field of force of an electromagnet 30. This electromagnet 30 is a duplicate of all of the other electromagnets 10 in the line, and all of said magnets are connected in the same circuit and all subjected to precisely the same influences. The electromagnet 30 is placed opposite the desired calling-pendulum and a circuit is then closed through a source of electrical energy 31 by a suitable key or switch 32. As a result every electromagnet along the line is energized, including the electromagnet 30, and the single calling-pendulum and every one of the responsive pendulums will be attracted.

When the calling-pendulum has reached the limit of its movement in the direction of the magnet, the circuit is immediately opened. It has been stated that all of the responsive pendulums are attracted; but in no case, with the exception of the responsive pendulum corresponding to the calling-pendulum, has any pendulum arrived at its exact period when the current is cut off. The calling-pendulum and the duplicate responsive pendulum then start at precisely the same time on the second half period of movement and move in unison until the second half period has been accomplished, while the operator watching the calling-pendulum may close the circuit and again energize all of the electromagnets.

While all of the responsive pendulums have started on their second half period during the movement of the selected responsive pendulum, the movement is irregular and occurs either before or after the correct time, and this is accentuated when said pendulums arrive at the end of their first half periods, the second closing of the electromagnet occurring at the proper time for the selected responsive

pendulum, but not at a time which will permit proper action of the non-selected responsive pendulums.

In operation any substation will call central 5 by short-circuiting the line 18 19 through a battery 34 by a switch 35. He then removes his receiver from the hook, and thus allows the contact-arm 15 to descend into engagement with the contact-arm 16 and completes 10 the talking-circuit. The subscriber then asks for the required number and the central-station operator moves the electromagnet 30 in front of the desired calling-pendulum and starts the movement, as before described, until 15 the responsive pendulum at the selected station strikes the arm 15 and causes it to fall into engagement with the arm 16, thus establishing a calling-circuit at the selected station, and a current then sent along the line will energize 20 the calling-bell of the selected station. The subscriber at the called station then removes his receiver from the hook and by closing the primary circuit is enabled to converse with the calling subscriber.

25 It will be observed that with an apparatus of this character all of the telephone instruments in the line are disconnected and will not be injured during an electrical storm, and, further, that any substation may be 30 called up without the knowledge of any of the other stations.

Having thus described the invention, what is claimed is—

1. In signaling apparatus, a pair of superposed contact members, a receiver-hook having its inner end arranged to form a support for the upper member, the removal of the receiver from the hook permitting such upper member to descend into engagement with the 40 lower member, and the replacing of the receiver serving to separate said members, and

an electromagnetically-controlled pendulum for moving the upper member from the support.

2. In signaling apparatus, a pair of superposed contact members, a pivotally-mounted receiver-hook having at its inner end a support for the upper member and provided with an inclined arm extending below the support to permit reengagement with said upper 50 member after a circuit-closing operation, and an electromagnetically-controlled pendulum for moving the upper member from said support.

3. In signaling apparatus, a pair of superposed contact members, a receiver-hook having at its inner end an insulated support for the upper member, and provided with a pendent arm arranged in a plane oblique to the vertical plane of said upper member, and an 60 electromagnetically-controlled pendulum for moving said upper member from its support.

4. In signaling apparatus, a lower contact member in the form of a bar having an in-turned arm at one end, a second contact member 65 arranged above the first and adapted to engage said arm to close a circuit, a pivotally-mounted receiver-hook having at its inner end a support for said upper member, and provided with a pendent inclined arm to permit reengagement with said upper member after a circuit-closing operation, and an electromagnetically-controlled pendulum for moving said upper member from its support.

In testimony that I claim the foregoing as 75 my own I have hereto affixed my signature in the presence of two witnesses.

DAVID FRAME LAUGHLIN.
